United States Patent Office.

BENJAMIN GREEN MARTIN, OF NEW YORK, N. Y.

Letters Patent No. 89,781, dated May 4, 1869.

IMPROVEMENT IN STOP-VALVES.

The Schedule referred to in these Letters Patent and making part of the same.

To all whom it may concern:

Be it known that I, BENJAMIN GREEN MARTIN, of the city, county, and State of New York, have invented a new and useful Improvement in Steam-Valves; and I do hereby declare that the following is a full, clear, and exact description of the same, reference being had to the accompanying drawings, which form part of this specification, and in which is represented a vertical section of a steam-valve, constructed according to my improvement.

This invention consists in a valve-plug of novel construction, whereby a simple and efficient steam-valve is obtained.

Referring to the accompanying drawings—

A represents the outer box, having the usual induction and eduction-passages, and an upwardly-extending central chamber, E, of square or quadrilateral form in its transverse section, and having, also, formed in it, an inclined valve-seat, a, arranged across the inlet-passage.

Arranged so as to close upon the inclined seat a is a vertically-sliding valve-plug, B B'.

Said valve-plug is fitted to slide within the chamber E, and it consists of a loose face, or valve-plate B, and a wedge, B'; is square, or quadrilateral in its transverse section, and is supported by a threaded stem, b, which fits and works in a female-threaded hollow stem, C.

Said stem C is arranged longitudinally within a cap, D, which is screwed into the top of the outer box A, and it is provided with a rotary, without a longitudinal motion, so that by turning the same the valve-plug B B' may be raised from or lowered to the seat a.

The said valve-plate B of the plug B B' is made to conform loosely to three sides, or rather to the top and bottom and one side of the wedge B' of the said plug, so as to allow a limited longitudinal movement of the wedge independently thereof, and is connected thereto by the passing of the stem b through a slot, s, in its upper side, and a pin, o, through a slot in its lower side.

Said slots are made to fit loosely around the said stem and pin, so as to allow a limited lateral play to the said valve-plate B.

Coiled around the stem b, between the upper side or top of this valve-plate B and a collar, c, on the stem, is a spiral spring, e, for the purpose of holding

the said valve-plate against the but of the wedge, thereby preventing shaking of the parts when the valve is open, and also so that the valve may be used in an inverted or other position, when desirable.

The rotary stem C is provided, at its bottom, with a circular flange, or head d, fitted and ground into the dome of the cap D, so that the upward pressure of the steam against its under side will cause its closer fitting to the dome, for the purpose of preventing leakage, and thereby obviate the necessity of using packing.

This flange, or head d, is held against the said dome, when not acted upon by the steam, by means of a spiral spring, g, arranged between the upper extremity of the cap D and a collar, f, on the said stem C.

Provision is made for dressing and truing the seat a, and the flat surfaces of the square, or quadrangular chamber E, by means of an opening made through the box A, and directly under the bottom of the said chamber E and seat a. Said opening is afterward closed with a screw-cap, o.

The operation of this valve is such that when the stem C is turned, the valve-plug B B' is carried up or down, according as the stem is turned backward or forward, the back or straight side of the wedge B' sliding against the perpendicular surface of the wall of the chamber E.

Upon turning the stem in such manner as to lower the plug, the valve-plate B will seat itself upon the seat a, and at the same time rest its lower end upon the bottom of the chamber E, whereupon a continued turning of the said stem C will cause the wedge B', in passing still further downward, while the said plate remains stationary, to wedge the said plate more tightly against the seat a, thereby effectually shutting off the steam.

What I claim as my invention, and desire to have secured by Letters Patent, is—

The valve-plug B B', consisting of the valve-plate B, and the wedge B', whereby the plug, when seated, is expanded by the downward movement of the wedge, substantially as herein described.

BENJN. GREEN MARTIN.
